[57] **CLAIM**

The ornamental design for a tape recorder combined with a disc player and receiver, as shown and described.

DESCRIPTION

FIG. 1 is a partial perspective view of a tape recorder combined with a disc player and a receiver showing my new design;

FIG. 2 is a top plan view thereof;

FIG. 3 is a left side elevational view thereof, a right side elevational view thereof being a mirror image;

FIG. 4 is a front elevational view thereof;

FIG. 5 is a rear elevational view thereof;

FIG. 6 is a perspective view of a second embodiment of a tape recorder combined with a disc player and a receiver showing my new design;

FIG. 7 is a top plan view thereof;

FIG. 8 is a left side elevational view thereof;

FIG. 9 is a front elevational view thereof;

FIG. 10 is a bottom plan view thereof;

FIG. 11 is a right side elevational view thereof; and,

FIG. 12 is a rear elevational view thereof.
